PORTABLE HYDRAULIC POWER PUMP

Stanley J. Rhodes, 2702 S. 46th St., Milwaukee 15, Wis.,
assignor of one-half to Arthur F. Zeman

Filed Aug. 22, 1962, Ser. No. 71,410

Term of patent 7 years

(Cl. D65—1)

FIG. 1.

FIG. 2.

FIG. 3

FIG. 1 is a perspective view of a portable hydraulic power pump showing my new design;

FIG. 2 is a reduced side elevation view thereof, as seen from the left relative to FIG. 1;

FIG. 3 is a reduced side elevation view thereof, as seen from the rear relative to FIG. 1.

I claim:

The ornamental design of a portable hydraulic power pump, as shown.
